SLIDING DOOR FOR DISPLAY CASES

Harry E. Case, Trenton, N. J., assignor to The
Luzerne Rubber Company, Trenton, N. J., a
corporation of New Jersey

Application March 27, 1936, Serial No. 71,288

9 Claims. (Cl. 312—189)

The present invention relates to improvements in display cases, and more especially to those of the class having sliding doors to provide access thereto and which are removable from the case, 5 the invention relating more particularly to display cases such as employed by butchers which are refrigerated.

In cases of this class, a pair of sliding doors are usually employed, the doors having grooves 10 in their upper and lower edges which cooperate with rails on the upper and lower frames of the door opening, the doors overlapping while they are both in closed position, the doors being movable upwardly to disengage them from the lower 15 rails and thus permit insertion and removal thereof, but in cases of this kind as heretofore constructed the clearance spaces provided above the doors to permit raising thereof and the groove in the upper edge of the outer door leaves 20 a passageway which allows air to enter or to flow from the interior of the case, which is objectionable, especially in refrigerator cases.

The primary object of the present invention is to provide novel and improved means for preventing such passage of air into or out of the case while the doors thereof are closed and, at 25 the same time, permitting lifting of either of the doors, whenever necessary, to permit removal thereof, without requiring that the door be brought to any particular position for such purpose.

Another object of the invention is to provide such air sealing means which is readily applicable to cases of this class and which avoids the necessity of notching the doors or otherwise mutilating the parts thereof.

To these and other ends, the invention consists in certain improvements and combinations and arrangements of parts, all as will be hereinafter more fully described, the features of novelty being pointed out more particularly in the claims at the end of this specification.

In the accompanying drawing:

Figure 1 is an elevation of a portion of a display case embodying the present invention;

Figure 2 is a vertical section, on an enlarged scale, taken on the line 2—2 in Fig. 1;

Figure 3 is a vertical section taken on the line 3—3 in Fig. 2, and

Figure 4 is a detail perspective view of the sealing block according to the present invention.

Similar parts are designated by the same reference characters in the several figures.

The present invention is applicable generally 55 to display cases and the like having doors slid-

ably mounted therein so that they may be opened and closed, and more especially to cases in which the sliding doors are removable, as by lifting them in the door opening. The invention is more particularly applicable to butchers' display cases or the like which are refrigerated, it providing novel and improved means for sealing the space heretofore left above the doors in cases of this class so as to prevent leakage of air from the outside of the case into the case, or vice versa, 10 and the improved sealing means provided by the present invention enables one or another of the doors to be removed from the case, when desired or necessary, while the door occupies any position along its guides, that is, without requiring that the door to be removed be brought to any particular position in the door opening.

The preferred embodiment of the invention is shown in the accompanying drawing wherein 1 represents a display case which may be of a usual form such as used by butchers and provided with any usual means for refrigerating it, a side of the case having a door opening 2 in which a pair of doors 3 and 4 are slidable horizontally, these doors being of such dimensions 25 in the direction of the length of the door opening as to overlap at their inner ends when fully closed, as shown in Fig. 1, either door however, being movable from its closed position toward the other end of the door opening to permit access to 30 the interior of the case.

The doors are mounted to slide on horizontal rails provided at the upper and lower edges of the door opening. In the present instance, upper and lower frame members 5 and 6 are provided for guiding the doors, these frame members being preferably composed of hard rubber and may be channel shaped in cross section to receive the upper and lower edges of the case as shown in Fig. 2, the upper frame member 5 having 40 upwardly extending flanges 7 which embrace the inner and outer walls of the case at the top of the door opening and the lower frame member 6 having downwardly extending flanges 8 to embrace the inner and outer walls of the case 45 at the bottom of the door opening. The upper frame member 5 is provided with a pair of downwardly projecting parallel ribs or rails 9 and 10 to project into grooves 11 and 12 formed in and extending throughout the lengths of the upper 50 edges of the doors 3 and 4, and the lower frame member 6 is provided with a pair of upwardly projecting parallel ribs or rails 13 and 14 adapted to slidably engage in grooves 15 and 16 formed in and extending longitudinally through- 55

out the lengths of the lower edges of the doors 3 and 4 respectively. These upper and lower rails 9 and 10 and 13 and 14 extend continuously throughout the lengths of the upper and lower edges of the door opening and slidably guide the doors in their movements into open and closed positions. The upper edges of the doors are spaced from the lower face of the upper frame member 5 and the grooves 11 and 12 in the upper edges of the doors are sufficiently deep to permit either of the doors to be lifted from its lower rail 13 or 14 to disengage such rail from the groove in the lower edge of the door and thus permit the bottom of the door to be swung outwardly over the rail and thus removed from the case. To facilitate such outward swing of one or the other door for removal and also for insertion into the case by a reverse operation to that just described, the inner sides of the upper rails 9 and 10 are preferably bevelled, as shown at 9a and 10a respectively. The doors 3 and 4 preferably each comprise a frame composed of hard rubber or other suitable material having glass panels 17 and 18 mounted therein by soft rubber strips 19 and 20 which form air tight joints around the edges of the glass panels, the edges of the glass panels being clamped respectively between inturned flanges 21 and 22 on the outer sides of the door frames and an angle iron 23 secured as by screws to the respective door frame and filled with a caulking compound 24 and a hard rubber glazing strip 25 secured to the respective door frame by screws 26. The doors in cases of this class, usually occupy an inclined position as shown in Fig. 2 in order to prevent inward and outward movement of the upper portions of the doors, due to the clearances between the grooves in the upper edges of the doors and the upper rails 9 and 10, but the present invention is equally applicable to doors which are mounted vertically, the sealing means provided by the present invention preventing such movement of the doors if mounted vertically.

In cases of this class as heretofore constructed, the clearance space provided above the upper edges of the doors for removal thereof and the upper groove in the outer door leave an open passageway, when the doors are fully closed, through which air may flow from the exterior to the interior of the case, or vice versa, and such leakage of air lowers the efficiency of refrigeration and is otherwise objectionable. The present invention provides means for sealing such passage against the entrance or escape of air without however, interfering with the removal or insertion of either of the doors so that either door may be removed or inserted at any position along the guiding rails. The sealing means according to the present invention comprises a sealing block 30 composed of hard rubber or other suitable rigid material which is inserted in a recess 31 formed in the upper frame member 5 and the wall of the case immediately above it in the region where the doors overlap when fully closed, although it may extend beyond such region of overlap, and is of a width necessary to extend over and close the space left above one or both doors. This sealing block for example, which is shown in the present instance applied to doors grooved at their upper edges to receive guide rails, is of a width to extend from the front wall of the upper outer rail 10 substantially to the front outer wall of the upper inner rail 9, the upper outer rail 10 being interrupted at a point centrally of its length as shown in Fig. 3

to accommodate the sealing block. The rear portion 32 of the sealing block is of a width and vertical height to bear on the upper edges of the doors 3 and 4 between the upper grooves 11 and 12 therein, and the sealing block is provided with an extension 33 which projects downwardly beyond the portion 32 thereof and is of a width and depth to fit closely in the upper groove 12 in the outer door and engage the bottom of this groove and thus fill it, as shown in Fig. 2. The portion of the sealing block above the upper frame member 5 is provided with lugs or extensions 34 which are arranged to rest on the upper side of this frame member when the sealing block occupies its normal operative position with the portion 32 thereof engaging the upper edges of the doors and the extension 33 thereof filling the upper groove in the outer door, these lugs preventing dropping of the sealing block from its recess when the doors are removed from the case. The sealing block may be maintained in sealing engagement with the upper edges of the doors by gravity, it being yieldable upwardly in its recess when either door is lifted for removal or insertion. It is preferable however, to provide means for yieldingly holding the sealing block in its operative sealing relation with the upper edges of the doors, as by providing a body of sponge rubber 35 or other suitable yielding means in the recess above the sealing block and which will be compressed when the sealing block is forced upwardly by the lifting of either door for removal or insertion, such yielding means however, maintaining the sealing block normally in sealing relation with the doors.

By mounting a sealing block according to the present invention in the upper frame member of the door opening, effective closing of the space above the upper edges of the doors where the doors overlap when closed, is accomplished, thus effectively preventing the flow of air into or out of the case through such space, and by mounting the sealing block yieldingly in its recess, either of the doors may be removed from and inserted in the case while at any point along the length of its guiding rails by merely lifting such door to release its lower edge from its lower guiding rail and then swinging such door outwardly, the sealing block moving upwardly in its recess to accommodate such lifting movement of the door. Since the upper edges of the doors with which the sealing block cooperates are continuous or unnotched throughout their lengths, no openings are left through which air may pass into or out of the case.

According to the particular embodiment of the present invention shown and hereinbefore described, both of the doors may be opened and closed by sliding them longitudinally along their rails, the sealing block bearing slidably on the upper edges of the doors between the grooves therein and in the upper groove of the outer door, and when the doors are fully closed their inner ends will overlap in the region opposite to the sealing block as shown in Fig. 1, the portion 32 of the sealing block which bears on the upper edges of the inner and outer doors between the grooves therein then filling the space between these portions of the upper edges of the doors and the upper frame member 5 and also closing the groove 12 in the outer door, thus preventing the passage of air through these spaces, the substantial filling of the upper grooves 11 and 12 by the upper rails 9 and 10 closing these grooves at each side of the sealing block against

the direct passage of air into or out of the case. Removal of either door may be effected by simply lifting such door, while at any point along the length of its rails until its lower edge 5 is free to swing outwardly over its lower rail, and then swinging the lower portion of the door outwardly, the sealing block yielding upwardly sufficiently to permit such lifting movement of the door, and although the rib or extension 33 10 fits closely in and substantially closes the groove 12 in the top of the door 4, the block fits sufficiently loosely in its recess and its sponge rubber or resilient backing is sufficiently yieldable to allow the block to tilt slightly and thus permit 15 removal of the door without binding on the sealing block. Insertion of either door into the case at any point along the length of the guiding rails may be similarly accomplished by first engaging the upper edge of the door with its upper 20 rail then lifting the door sufficiently to permit its lower end to be swung inwardly over its lower rail after which the door is lowered into its operative position, the sealing block yielding upwardly during the lifting of the door 25 incident to its insertion into the case. After the door has been lowered to its normal operative position on its lower rail, the sealing block will automatically move downwardly by gravity or under the action of the sponge rubber member 30 35 or other yielding means to bring it into air sealing engagement with the doors. When the sealing block is applied to doors which are mounted vertically instead of inclined as shown, the close fitting of the rib 33 thereon in the groove 12 in the top of the outer door will prevent the doors from swinging inwardly and outwardly.

What I claim is:—

1. A display case having a door frame comprising upper and lower members provided with rails, a plurality of doors slidable on the rails in the door frame and overlapping while in closed position, the doors being movable upwardly in the frame for removal, and a sealing member fitted in the upper frame member and engaging the tops of the doors where they overlap when closed to form an air seal at that point between the tops of the doors and the upper door frame member, said sealing member being movable upwardly to permit removal of a door from the case while the door occupies any position in the case.

2. A display case having a door frame comprising upper and lower members provided with rails, a pair of doors grooved at their upper and lower edges to slide on the rails and overlapping while closed, and a sealing member having a portion engaging the upper edges of the doors where they overlap and having another portion engaging in and filling the groove in the upper edge of the outer door, said sealing member being fitted in the upper frame member to move upwardly and thereby permit lifting one or the other of the doors for insertion or removal.

3. A display case having a door frame comprising upper and lower members provided with rails, a pair of doors grooved at their upper and lower edges to slide on the rails and overlapping while closed, the doors being movable upwardly in the frame for removal, the upper frame member having a recess therein adjacent to the region where the doors overlap when closed, and a sealing member fitted in said recess and having portions slidably engaging the upper edges of the

doors and in the groove in the upper edge of the outer door, said sealing member being movable upwardly in said recess to permit lifting of one or the other door for removal.

4. A display case having a door frame comprising upper and lower members each provided with a pair of rails, a pair of doors grooved at their upper and lower edges to slide on the rails and overlapping while closed, one of the rails on the upper frame member being interrupted adjacent the region of the overlapping portions of the closed doors, the doors being movable upwardly in the frame for removal, and a sealing member located in the interruption in the upper rail and having portions slidably engaging the top edges of the doors and in the groove in the top edge of the outer door, said sealing member being movable upwardly with respect to the upper frame member when one or the other of the doors is lifted.

5. A display case having a door frame comprising upper and lower members each provided with a pair of rails, a pair of doors grooved at their upper and lower edges to slide on the rails and overlapping when closed, one of the rails on the upper frame member being interrupted in the region where the doors overlap when closed and the upper frame member having a recess adjacent to said rail interruption, and a sealing block fitted in said recess and rail interruption to yield upwardly therein and slidably engaging the upper edges of the doors to seal the spaces between said edges and the upper frame member and having a portion fitting in the groove in the upper edge of the outer door.

6. A display case having a door frame comprising upper and lower members each provided with a pair of rails, a pair of doors grooved at their upper and lower edges to slide on the rails and overlapping when closed, one of the rails on the upper frame member being interrupted in the region where the doors overlap when closed and the upper frame member having a recess adjacent to said rail interruption, and a sealing block fitted in said recess and rail interruption to yield upwardly therein and slidably engaging the upper edges of the doors to seal the spaces between said edges and the upper frame member and having a portion fitting in the groove in the upper edge of the outer door, said sealing block having projections thereon engageable with the upper frame member to limit the downward movement of the sealing block.

7. A display case having a door frame comprising upper and lower members each provided with a pair of rails, a pair of doors grooved at their upper and lower edges to slide on the rails and overlapping when closed, one of the rails on the upper frame member being interrupted in the region where the doors overlap when closed and the upper frame member having a recess adjacent to said rail interruption, a sealing block fitted in said recess and rail interruption to yield upwardly therein and slidably engaging the upper edges of the doors to seal the spaces between said edges and the upper frame member and having a portion fitting in the groove in the upper edge of the outer door to close it, and means in said recess and operative on the sealing block to yieldably force it downwardly to engage the upper edges of the doors.

8. A door frame comprising upper and lower members, a plurality of doors slidable in the door frame and overlapping while in a closed position; the doors being movable upwardly in the frame

for removal, and a closure member fitted in the upper frame member, and engaging the top of at least one of the doors to form a closure between the top thereof and the upper frame member, said closure member being movable upwardly to permit removal of a door from the case while such door occupies any position in the case.

5. A door frame for a display case comprising upper and lower frame members, a plurality of 10 doors slidable in the door frame and movable

upwardly in the frame for removal, and a closure member fitted in the upper frame member and engaging the top of at least one of the doors to form a closure between the top thereof and the upper frame member, said closure member being 5 movable upwardly to permit removal of the door from the case while such door occupies any position in the case.

HARRY E. CASE. 10
